UNITED STATES PATENT OFFICE.

HENRY J. CARBIS AND SAMUEL H. CARBIS, OF FREEPORT, PENNSYLVANIA, ASSIGNEES
OF ONE-THIRD TO THOMAS G. CORNELL, OF FREEPORT, PENNSYLVANIA.

VALVE.

1,120,594.

Specification of Letters Patent.

Patented Dec. 8, 1914.

Application filed March 4, 1914. Serial No. 822,471.

To all whom it may concern:

Be it known that we, HENRY J. CARBIS and SAMUEL H. CARBIS, citizens of the United States, residing at Freeport, in the county of Armstrong and State of Pennsylvania, have invented a new and useful Valve, of which the following is a specification.

The present invention appertains to valves, and aims to provide a novel and improved valve construction.

It is the object of the present invention, to provide a valve embodying a plug or spigot, and provided with unique means whereby when the plug or spigot is rotated to open position, the same will be moved longitudinally slightly to create a slight clearance between the plug or spigot and its bore, for clearing the adjoining portions of the plug and its bore, of any corrosion, sediment and other extraneous matter, the plug or spigot being returned to normal position when the same is opened and closed, to facilitate the regrinding action between the plug and its bore or seat.

It is also within the scope of the present invention to provide a valve construction of the nature indicated, which will be improved generally in its details, whereby the valve will be comparatively simple, durable and inexpensive in construction, as well as being simple, convenient, practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein—

Figure 1 is a longitudinal section of the valve, in open condition, parts being broken away. Fig. 2 is a similar section taken at right angles to the plane of section of Fig. 1. Fig. 3 is a cross section taken on the line 3—3 of Fig. 1. Fig. 4 is a cross section taken on the line 4—4 of Fig. 2.

The present invention embodies the shell or body 1 having the tapered bore or valve

seat 2 therein, and the inlet and outlet ports 3 extending to the bore 2, the bore 2 being disposed longitudinally of the body or shell 1, and the ports 3 protruding laterally for connection with the sections of the pipe between which the said valve is adapted to be interposed for controlling the flow of the fluid through the pipe. That end of the body or shell 1 adjoining the smallest end of the bore 2, is provided with a threaded counter bore or socket 4, while the other end of the body or shell is provided with a counter bore or socket 5, which is also threaded.

A tapered plug or spigot 6 is mounted snugly within the bore or valve seat 2, and is provided with a diametrical passage 7 adapted to be swung into and out of registration with the ports 3 of the shell or casting 1. The lower or large end of the plug 6 is provided with a depending boss or lug 8 projecting into the counter bore or socket 5.

In order to spring press the plug 6 snugly or tightly within the bore 2, a cup 9 is provided with a relatively thick outturned flange 10 at its rim or margin, has the flange 10 threaded into the counter bore or socket 5 adjoining, but spaced slightly from, the largest end of the plug 6. A binding or retaining nut 11 is threaded into the counter bore 5 to contact with the flange 10, for locking the cup 9 in place, it being noted that the mouth or open end of the cup is disposed innermost or uppermost so as to receive the boss or lug 8 of the plug. The binding or jam nut 11 is preferably locked or retained within the counter bore 5, by means of a split locking ring 12 snapped into an inner annular groove 13 provided in the walls of the counter bore 5.

An adjusting screw 14 is threaded through the bottom of the cup 9, and is provided in its upper or inner end with a concaved seat or recess 15, and a disk or spring seat 16 disposed loosely within the cup 9, has a rounded knob or lug 17 engaging the seat 15 of the adjusting screw, to enable the disk or spring seat 16 to rotate or vibrate with respect to the adjusting screw. Coiled wire compression springs

18 are seated between the disk 16 and the lower or largest end of the plug 6, around the boss 8. Attention is directed to the fact, at this point, that the disk or spring seat 16 being rotatable, will enable the springs 18 and seat 16 to rotate or swing

105
110

with the plug or spigot 6, to avoid friction between the springs and the plug, and to enable the plug to be forced snugly within the bore 2 in the most effective manner.

5 The disk or spring seat 16 will readily accommodate itself to the springs 18, and their tension may be regulated by adjusting the screw 14, as will be evident.

In order to manipulate or rotate the plug or spigot 6, a collar or ring 19 is threaded into the counter bore or socket 4 at the upper end of the shell or casing 1, a binding nut 20 being threaded upon the upper or outer end of the ring 19 and bearing against the corresponding end of the body or shell 1 to retain the ring 19 in place. The ring 19 is provided with a stuffing box 21, into which is threaded a gland 22, and a smooth valve stem 23 is journaled through the ring or stuffing box member 19 and the gland 22, the gland serving to compress the packing within the stuffing box 21 so as to embrace the stem 23 to prevent leakage.

The lower end of the stem 23 projects below the stuffing box member or ring 19, and is provided with a diametrical tongue 24, the ends of which project beyond the sides of the stem 23, to form fingers or projections, snugly engaging the upper or smallest end of the plug 6, and working between a pair of sectoral stops 25 formed upon the upper or smallest end of the plug. In this manner, the stem 23 which is independent of the plug, has limited oscillatory movements relative to the plug, it being noted that when the stem 23 is rotated in one direction, the fingers 24 will engage certain sides of the stops 25 to rotate or swing the plug with the stem, and when the stem is rotated in the opposite direction, the fingers 24 will engage the other sides of the stops 25 to correspondingly move the plug.

In order to depress or move the plug longitudinally against the tension of the springs or yieldable lifting means 18, a ring or annulus 26 is mounted within the lower or inner end of the counter bore 4, and loosely embraces the lower or inner end of the stem 23, the ring or annulus 26 being provided at diametrically opposite points, with depending cams 27 lying in the paths of the fingers 24. The ring 26 is disposed above the fingers 24, and seats against the bottom of the stuffing box member 19, the ring 27 being restrained against oscillatory movements, by means of a lug or rib 28 formed upon one side of the ring 26 and engaging one of a series of notches 29 formed upon the interior of the counter bore 4. Thus, by engaging the projection or lug 28 with the respective notches 29, the ring 26 may be adjusted angularly, with respect to the plug and stem, for positioning the cams 27 to the points desired or most appropriate.

65 A pointer 30 is preferably carried by the

actuating stem 23, to operate with the corresponding end of the shell or casing 1, the shell or casing being preferably provided with indications thereon, co-operable with the pointer, whereby the positions of the 70 plug or spigot may be readily determined.

In operation, the ring 26 is so arranged, that when the plug is in closed position, the fingers 24 will be released from the cams 27, the springs 18 serving to force the plug 75 snugly or tightly into the bore 2. Thus, when the passage 7 of the plug is out of register with the ports 3, the plug will effectively close the ports 3. To open the valve, the stem 23 is rotated in one or the 80 other direction, causing the fingers 24 to engage the stops or projections 25 of the plug, to thereby correspondingly rotate the plug to bring the passage 7 thereof into registration with the ports 3. After the plug 6 has 85 been moved into open position, the fingers 24 are arranged to engage the cams 27, which will cause the stem 23 to be forced downwardly or longitudinally, to thereby move the plug or spigot 6 downward or longitudinally slightly to provide a slight clearance between the plug and the bore 2, whereby the corrosion, sediment or other foreign matter between the bore 2 and the plug 6 may be cleared out or ejected. As soon as the 90 stem 23 is rotated to close the valve, the fingers 24 will be released from the cams 27 to again return the plug 6 to normal position, under the influence of the spring 18, it being noted that as the plug is opened and 95 closed, the same will be given a slight longitudinal movement, which will facilitate the regrinding action between the plug and the bore 2, to cause the plug to engage snugly within the bore to prevent leakage when the 100 valve is closed.

It will therefore be manifest, that the present valve is of such construction, as to enhance or facilitate the regrinding action between the plug and its bore or seat, peculiar means being provided for actuating and spring pressing the plug or spigot to the ends desired. The other advantages and capabilities of the present valve will be obvious to those versed in the art and further 11: comment is deemed unnecessary.

Having thus described the invention, what is claimed as new is:

1. A valve embodying a body having a bore, a spring pressed plug fitting within 120 the bore, a rotary stem carried by one end of the body adjoining one end of the plug, the said end of the plug having stops, one end of the stem bearing against the said end of the plug and having a finger movable between the said stops, and a cam mounted within the body in the path of the said finger to move the stem longitudinally against the said end of the plug when the stem is at a predetermined position. 130

2. A valve embodying a body having a bore, a spring pressed plug fitting in the said bore, a member engaged in one end of the body adjoining one end of the plug, 5 a stem journaled through the said member, the said end of the plug having a pair of diametrically opposite stops, the inner end of the stem having a pair of fingers movable between the said stops, and a ring 10 mounted within the body around the inner end of the said stem, the ring seating against the said member and having cams disposed in the path of the said fingers for moving the stem longitudinally against the 15 said end of the plug, to move the plug longitudinally, when the stem is moved to a predetermined position.
3. A valve embodying a body having a bore, a spring pressed plug fitting in the 20 said bore, a member engaged in one end of the body adjoining one end of the plug, a stem journaled through the said member, the said end of the plug having a pair of
- diametrically opposite stops, the inner end of the stem having a pair of fingers movable between the said stops, a ring mounted within the body around the inner end of the said stem, the ring seating against the aforesaid member and having cams disposed in the paths of the said fingers for 25 moving the stem longitudinally against the said end of the plug to move the plug longitudinally, when the stem is moved to a predetermined position, the body having a series of notches and the said ring having 30 a lug engageable in said notches to hold the ring at a predetermined angular position.
- In testimony that we claim the foregoing as our own, we have hereto affixed our signatures in the presence of two witnesses.
